UNITED STATES PATENT OFFICE.

THOMAS J. CAHILL, OF SAN FRANCISCO, CALIFORNIA.

MEANS FOR LOCATING AND SECURING SUNKEN VESSELS TO HOISTING APPARATUS.

1,236,539.

Specification of Letters Patent. Patented Aug. 14, 1917.

Application filed December 8, 1916. Serial No. 135,780.

To all whom it may concern:

Be it known that I, THOMAS J. CAHILL, a citizen of Australia, and a resident of San Francisco, in the county of San Francisco and State of California, have invented a new and Improved Means for Locating and Securing Sunken Vessels to Hoisting Apparatus, of which the following is a full, clear, and exact description.

10 My invention relates to means for indicating the position of a sunken vessel, and also for presenting means whereby said vessel may be connected to hoisting apparatus.

An object of the invention is to provide a 15 simple and inexpensive indicator with which are associated means for securing a sunken vessel, the position of which is indicated by the device, to the lifting chain or cable of a hoisting apparatus.

20 With the above and other objects in view, the nature of which will more fully appear as the description proceeds, the invention consists in the novel construction, combination and arrangement of parts as herein 25 fully described, illustrated and claimed.

In the accompanying drawings, forming part of the application, similar characters of reference indicate corresponding parts in all the views.

30 Figure 1 is an elevation of the device applied to a sunken vessel;

Fig. 2 is an enlarged elevation of the means for securing a hoisting chain or cable to a sunken vessel;

35 Fig. 3 is a side elevation of the float which constitutes the indicator; and

Fig. 4 is a plan view of a vessel equipped with my device.

Referring to the drawings, 5 is a buoy connected by a flexible member 6 of suitable length to a hook 7. The hook is provided with a pair of rigid arms 8 disposed in the plane of the hook and directed upwardly from the lower end 9 of the hook which is 45 to be connected to a chain 10 secured to one side of a vessel 11. The two arms are directed oppositely and each carries a float 12 the buoyancy of which floats is sufficient to raise the chains associated with the hook. 50 These floats will maintain the hook 7 in an upright position, due to the fact that the arms 8 to which the floats are connected are rigid with the hook. The chain 10 passes through a link 13' of a chain 13 connected to 55 the opposite side of the vessel 11.

The flexible member 6 is engaged by a

chain link 14 which is maintained at the buoy 5 by a member 15. The link 14 is intended to be secured to a hoisting chain or cable, and when so secured the member 15 60 can be severed. The member 6 will then guide the link 14 into engagement with the hook 7.

To exert the pull only on the side of the vessel on which the vessel banks, the chain 65 10 is provided with a crossbar 16 adapted to engage the link 13'. When a pull is exerted on the hook 7, the crossbar 16 will come into engagement with the link 13', particularly if the pull is in the direction of the chain 13, 70 as shown in Fig. 1. Thereby the maximum pull will be applied to the side of the vessel to which this chain is connected. In case the pull is in the direction of the portion of the chain 10 below the cross bar 16, the maximum pull will be on the side of the vessel to which the chain 10 is connected, with substantially no pull on the other chain until the vessel is brought to a substantially upright position. 75

The provision of the crossbar on the chain 10 assures a maximum pull on any desired side of a vessel; and the provision of the floats on the hook 7 insures an upright position of the hook, and thereby it insures the 85 engagement of the link 14 therewith when it is lowered at the end of a lifting chain or cable from a hoisting apparatus. 80

I claim:

1. In combination, a pair of flexible members, one presenting a link through which the other flexible member passes, a crossbar carried by said other flexible member for engaging the link, a hook connected to said other flexible member, floats associated with 90 said hook for maintaining the hook in an upright position in water, a buoy, a flexible member connecting the buoy to the hook, a chain link carried by said flexible member, and a severable member connecting said 95 link to the buoy.

2. In combination, a pair of chains, one of said chains presenting a link through which the other chain passes, a crossbar on 100 said other chain for engaging the link, a hook connected to said other chain above the bar and the link, a pair of arms associated with the hook, a float carried by each of said arms for maintaining said hook in an upright position in water, a buoy, a flexible 110 member connecting the buoy to the hook, a chain link carried by said flexible member.

and a severable member connecting said link to the buoy.

3. In combination, a hook the body portion of which is adapted to be secured, a pair of arms connected to the body of the hook, a float carried by each of said arms so as to maintain the hook in an upright posi-

tion in water, a buoy, a flexible member connecting the buoy to the hook, a chain link carried by said flexible member, and a severable member connecting said link to the buoy. 10

THOMAS J. CAHILL.
